UNITED STATES PATENT OFFICE

HERBERT STAYTON HEWITT, OF SURBITON, AND WILFRED AMBROSE WHATMOUGH,
OF NEW BARNET, ENGLAND

COMBUSTION CHAMBER

Application filed March 7, 1929, Serial No. 345,153, and in Great Britain December 11, 1928.

This invention relates to the combustion chambers of internal combustion engines in which at least one valve is arranged in a cavity at the side of the engine. The object 5 of the invention is to provide improved filling and exhausting of the cylinder.

According to this invention a combustion chamber for an internal combustion engine comprises in combination a barrel, a lateral 10 cavity in communication with said barrel, a valve seating in the "inner wall" of said cavity, the outer wall of which cavity is so shaped that its contour in the direction of the flow of gases is concavely curved from 15 that edge of the valve seating which is remote from said barrel to at least a location above the center of the valve seating, and which inner wall as it extends towards the barrel slopes inwardly and meets the barrel 20 at an obtuse angle. The words "inner wall" denote that wall which is transverse to the axis of the cylinder and nearer the crank shaft of the engine.

When the cavity contains only the exhaust 25 valve, the passage preferably also widens towards the cylinder barrel.

The accompanying drawings are purely diagrammatic, and in these Figure 1 is a central vertical section of 30 part of a cylinder of an internal combustion engine taken through the centre of an inlet valve located in a lateral cavity,

Figure 2 is a similar view taken through the centre of an exhaust valve, and 35 Figure 3 is a horizontal view showing the shape of the cavity and the passage connecting it with the cylinder barrel when only an exhaust valve is located in the cavity.

Like numerals indicate like parts throughout the drawings.

The cylinder 2 is formed with a lateral cavity 3 in which an inlet valve 4 and an exhaust valve 5 are arranged side by side.

The seatings 6 and 7 for the valves are, as 45 usual, spaced from the cylinder barrel 2 by a part 8 of the casting which varies in width according to circumstances, generally varying with the width of the water space (not shown) around the barrel at that point. 50 This entails a passage 9 between the cavity

and the barrel, and in the present invention the bottom 10 of this passage curves downwards from a point close to the periphery of the valve seatings towards the cylinder barrel. For example, this surface may form 55 part of a circular cylinder whose axis 11 lies beneath the valve seatings. The curve 11 may terminate in a rounded edge 12 running gently into the straight wall of the cylinder barrel or not, as desired, and it is 60 not essential that the curved surface 10 should form part of a circular cylinder.

Preferably the actual contour is chosen in relation to the roof 13 of the passage so as to provide a gradually deepening passage 65 between the cavity 3 and the cylinder barrel 2 in which there is a minimum of disturbance to flow from the cavity to the barrel during the inlet stroke, and from the barrel to the cavity on the exhaust stroke. 70

During the inlet stroke, whilst the inlet valve 4 is at or near its maximum height, the inlet charge impinges on the underside of the valve, the head of which acts as a deflecting baffle tending, to a great extent, 75 to affect the flow along the passage. Preferably this is taken into consideration and the underside or neck 40 of the valve head is formed with a large radius to provide an easy deflection of the inlet charge.

The head of the exhaust valve also has an effect on the flow of the exhaust gases and is preferably shaped to conform to the path of these gases, being domed at 50 for this purpose.

When applying the present invention to a cylinder employing such valves, the shape of the bottom 10 of the passage between the cavity and the barrel is formed to agree with the lines of flow of the inlet charge and exhaust gases, and the roof 13 is shaped to conform to the flow lines over the head of the exhaust valve. The paths of the gases are indicated by the flow lines and arrows in Figures 1 and 2. It is therefore desirable, when determining the contour of the bottom and roof of the passage, to take into consideration the shapes of the neck of the inlet valve and the head of the exhaust valve.

Tests have proved that, if the passage is either restricted or incorrectly directed, the exhaust valve is heated by eddying flame. The consequence is that the rate of flame travel is increased, i. e., the angle of spark advance for a given engine speed is lowered. In fact it is possible by such bad design to make a fuel of a good anti-knock value into one which is inherently bad from a detonation point of view.

Also it has been found possible, by arranging the contour of the bottom of the passage in relation to the shape of the inlet valve head, to enhance considerably the filling of the cylinder by minimizing the resistance to flow, thus higher volumetric efficiency is obtainable.

With a relatively narrow cavity containing the exhaust valve alone, the passage 9 is widened towards the cylinder barrel, as well as deepened slightly, as shown in Figures 2 and 3.

What we claim as our invention and desire to secure by Letters Patent of the United States is:—

1. A combustion chamber for an internal combustion engine comprising in combination a barrel, a lateral cavity in communication with said barrel, a valve seating in the inner wall of said cavity, the outer wall of which cavity is so shaped that its contour in the direction of the flow of gases is concavely curved from that edge of the valve seating remote from the barrel to at least a location above the center of the valve seating and which inner wall as it extends towards the barrel is sloped inwardly towards the crank shaft to meet the barrel at an obtuse angle, which cavity varies gradually in cross section as it approaches the barrel.

2. A combustion chamber for an internal combustion engine comprising in combination a barrel, a lateral cavity in communication with said barrel, a valve seating in the inner wall of said cavity, the outer wall of which cavity is so shaped that its contour in the direction of the flow of gases is so concavely curved from that edge of the valve seating which is remote from the barrel and over and above the said seating that it conforms with the shape of the head of a valve associated with said seating and which inner wall as it extends towards the barrel is so convexly curved as to conform to the flow lines of the gases between the barrel and said lateral cavity and each cavity varies gradually in cross section as it approaches the barrel.

3. A combustion chamber for an internal combustion engine comprising in combination a barrel, a lateral cavity in communication with said barrel, a valve seating in the inner wall of said cavity, the outer wall of which cavity is so shaped that its contour

in the direction of the flow of gases is concavely curved from that edge of the valve seating remote from the barrel to at least a location above the center of the valve seating, and which inner wall as it extends towards the barrel is so sloped inwardly that it meets the barrel at an obtuse angle and provides a passage connecting said cavity with said barrel which deepens towards the barrel.

4. A combustion chamber for an internal combustion engine comprising in combination with said barrel, a valve seating in the inner wall of said cavity, the outer wall of which cavity is so shaped that its contour in the direction of the flow of gases is concavely curved from that edge of the valve seating remote from the barrel to at least a location above the center of the valve seating and which inner wall as it extends towards the barrel is so inwardly and convexly curved towards the crank shaft of the engine that it provides a passage connecting said cavity with said barrel which deepens towards the barrel.

5. A combustion chamber for an internal combustion engine comprising in combination a barrel, a lateral cavity, a passage connecting said cavity with said barrel, an exhaust valve seating in the inner wall of said cavity the outer wall of which cavity is so shaped that its contour in the direction of the flow of gases is concavely curved from that edge of the valve seating which is remote from the barrel to at least a location above the center of the valve seating, the width and depth of which cavity and passage as they extend towards the barrel increase and which inner wall as it extends towards the barrel slopes inwardly and meets the barrel at an obtuse angle.

6. A combustion chamber for an internal combustion engine comprising in combination a barrel, a lateral cavity in communication with said barrel, a valve seating in the inner wall of said cavity, the outer wall of which cavity is so shaped that its contour in the direction of the flow of gases is concavely curved from that edge of the valve seating to at least a location above the center of the valve seating, and which inner and outer walls as they extend towards the barrel are so sloped inwardly that the distance between them gradually increases from the cavity to the barrel.

7. A combustion chamber for an internal combustion engine comprising in combination a barrel, a lateral cavity in communication with said barrel, a valve seating in the inner wall of said cavity, the outer wall of which cavity is so shaped that its contour in the direction of the flow of gases is concavely curved from that edge of the valve seating remote from the barrel to at least a location above the centre of the valve seat-

ing and from thence in a smooth concave curved surface over the barrel and which inner wall as it extends towards the barrel slopes inwardly and meets the barrel 5 at an obtuse angle.

8. A combustion chamber for an internal combustion engine comprising in combination a barrel, a lateral cavity in communication with said barrel, a valve seating in the 10 inner wall of said cavity, the outer wall of which cavity is so shaped that its contour in the direction of the flow of gases is concavely curved from that edge of the valve seating remote from the barrel to at least 15 a location above the centre of the valve seating and from thence extending in an unbroken smooth concave curve over the barrel and terminates in proximity to that edge thereof remote from the valve, and 20 which inner wall as it extends toward the barrel slopes inwardly and terminates at the cylinder barrel with a rounded edge.

9. A combustion chamber for an internal combustion engine comprising in combination a barrel, a lateral cavity in communication with said barrel, a valve seating in the inner wall of said cavity, the outer wall of which cavity is so shaped that its contour in the direction of the flow of gases is concavely curved from that edge of the valve seating remote from the barrel to at least 25 a location above the centre of the valve seating and from thence extends in a smooth concave curve over the barrel and terminates 30 in proximity to that edge thereof remote from the valve in a convex curve, and which inner wall as it extends towards the barrel is so sloped inwardly that it meets the barrel at an obtuse angle and provides a passage 35 40 connecting said cavity with said barrel which deepens towards the barrel.

10. A combustion chamber for an internal combustion engine comprising in combination a barrel, a lateral cavity in communication with said barrel, a valve seating in the inner wall of said cavity, the outer wall of which cavity is so shaped that its contour in the direction of the flow of gases is concavely curved from that edge of the 45 50 valve seating remote from the barrel to reach its greatest height at a point immediately above the centre of the valve seating, and which inner wall as it extends towards the barrel is so sloped inwardly that it 55 meets the barrel at an obtuse angle and provides a passage connecting said cavity with said barrel which deepens towards the barrel.

11. A combustion chamber for an internal combustion engine comprising in combination a barrel, a lateral cavity in communication with said barrel, a valve seating in the inner wall of said cavity, the outer wall of which cavity is so shaped that its 60 65 70 75 80 85 90 95 100 105 110 115 120 125 130 contour in the direction of the flow of gases

is concavely curved from that edge of the valve seating remote from the barrel to at least a location above the centre of the valve seating and from thence in a smooth concave curved surface over the barrel and terminating in proximity to the edge thereof remote from the valve and which inner wall as it extends towards the barrel slopes inwardly and meets the barrel at an obtuse angle.

12. A combustion chamber for an internal combustion engine comprising in combination a lateral cavity in communication with said barrel, a valve seating in the inner wall of said cavity, a poppet valve associated with said seating, the outer wall of which cavity is so shaped that its contour in the direction of the flow of gases is concavely curved from that edge of the valve seating remote from the barrel to at least a location above the centre of the valve seating, and that the distance between said outer wall and the valve head measured in any direction with the valve at full lift is substantially constant, and which inner wall as it extends towards the barrel is convexly curved about an axis which is disposed transversely to the axis of the cylinder and externally of the inner periphery of the barrel, and the distance between the inner wall and the underside of the head is substantially equal to the distance between the valve head and said outer wall.

In testimony whereof we have signed our names to this specification.

HERBERT STAYTON HEWITT.

WILFRED AMBROSE WHATMOUGH.
